UNITED STATES PATENT OFFICE.

EDWIN SCOTT VOTEY, OF SUMMIT, NEW JERSEY.

COMBINED PLAYER-PIANO AND PHONOGRAPH.

1,119,906.

Specification of Letters Patent.

Patented Dec. 8, 1914.

Application filed August 2, 1913. Serial No. 782,556.

To all whom it may concern:

Be it known that I, EDWIN S. VOTEY, a citizen of the United States, and resident of Summit, in the county of Union and State of New Jersey, have invented certain new and useful Improvements in Combined Player-Pianos and Phonographs, of which the following is a specification.

This invention relates to improvements in combined player pianos and phonographs.

The object of my invention is to provide a new and improved instrument of this kind which is simple in construction, effective and reliable in action and in which the phonograph record disk while being started and until it has the proper speed of rotation is driven jointly by the phonograph spring motor and by the air motor of the player piano which is used for moving the perforated music sheet and after the disk has obtained the proper speed the air motor is automatically thrown out of operative connection with said disk or its support so that the disk is driven by its spring motor only, thus making it possible to obtain proper synchronism between the record disk and the perforated music sheet from the start.

In the accompanying drawings:—Figure 1 is a front elevation of a combined piano player and phonograph embodying my invention. Fig. 2 is an end elevation of the same, parts being broken away and others shown in section. Fig. 3 is a plan view of the same, the top of the piano casing being removed and parts being broken away. Fig. 4 is a side view of the clutch and clutch operating means, parts being shown in section. Fig. 5 is a transverse sectional view on the line a—a of Fig. 4. Fig. 6 is a face view of the beginning part of the perforated music sheet to be used in connection with the instrument. Fig. 7 is a plan view of the record disk. Fig. 8 is a diagrammatic view showing the air motor, clutch, tracker and the relation and connections of the several parts.

The player piano is provided with the conventional casing 1 in the upper front part of which there is a chest 2 containing the tracker 3, the music roll 4 and the take-up roll 5, which music and take-up rolls are driven in the conventional manner by means of an air motor 6 of any approved construction and connected with the take-up and music-rolls by any well known motion transmitting gearing, all of which forms no par-

ticular part of the present invention. The rotative support 7 for the phonograph or talking machine record 8 is provided above the top of the chest 2 at the front of the piano casing 1 and is driven by a spring motor 9 such as is commonly used for rotating a talking machine record in the conventional way. The phonograph record support 7 and the perforated music sheet 10 are provided with suitable contrivances for operating, at regular intervals, valves or like devices which control the movements of a regulator which in turn controls the speed of the air motor 6 for the perforated music sheet, but these mechanisms form no part whatever of the present invention and may as well be substituted by others as far as the present invention is concerned.

The perforated music sheet 10 is provided in advance of the ordinary music slots or perforations 11 along one edge, preferably the right hand edge, with a slot 12 of greater or less length, which can register with a supplemental tracker duct 13 in the tracker 3. From this tracker duct 13 a tube 14 leads to valves 15 and from the latter a tube 16 leads to a bellows 17, the movable board of which is connected with a means for engaging the conventional brake lever 18 for the talking machine record support, so that when this bellows is collapsed the brake lever is disengaged from the talking machine record support 7 so that the latter is now free to rotate. A branch tube 19 connected with the tube 16 leads to a bellows 20, to the movable board of which is attached an arm 21 connected with a rod 22 which is pivoted to a lever 23 having a pin 24 entering a groove 25 in a collar 26 on a shaft 27 driven by the air motor 6. On the end of the shaft 27 a clutch member 28 is fixed which can be engaged with a clutch member 29 fixed on the shaft 30 operatively connected by suitable power gearing 31 with the spring motor 9 for the record disk. When the two clutch members 27 and 28 are disengaged the spring motor for the phonograph disk operates entirely independent of the air motor 6, but as long as these two clutch members are engaged the spring motor 9 for the talking machine record support is assisted by the air motor 6. When the beginning of the slot 12 in the perforated music sheet 10 arrives at the tracker duct 13 air is admitted to the valves 15 controlling the bellows 17 and 20 which are thus col-

lapsed whereby the brake lever 18 is moved to release the record support 7 and at the same time, by the collapsing of the bellows 20 the clutch members 28 and 29 are engaged 5 so that the spring motor is now assisted by the air motor and thus the disk is immediately started at the required speed as distinguished from the rather sluggish rotative movement which the disk support 10 would have at the beginning if started by the spring motor only. By the time that the rear end of the slot 12 arrives at the tracker duct 13 the disk support 7 has acquired the requisite speed and by the closing 15 of the tracker duct 13 by the imperforate part of the paper of the music sheet the valves 15 of the bellows 17 and 20 are so operated as to permit the expansion of these bellows by their conventional extending springs, with the result that the clutch members 28 and 29 are disengaged and the brake lever is held in disengaged position from the rim of the record support 7 by the usual locking device, provided for such 20 brake lever, and which locking device *per se* forms no part of the present invention.

It will thus be seen that the perforated music sheet is provided with a slot which determines the starting of the spring motor. 30 It is essential that there shall be a proper relation between the starting of the spring motor and the music slots in the perforated music sheet. For this purpose the record disk 8 is provided with a depression or recess 32 into which the needle 33 of the phonograph sound box 34 is placed before the mechanism is started so that when the disk starts rotating, the disk and perforated music sheet will be in perfect synchronism, 40 which synchronism is to be maintained by the devices previously mentioned, but which form no part of the present invention. However, it is necessary that the depression or recess 32 be in a certain position and 45 this is indicated by the pointer 35 preferably extending over the rim of the record support 7 and by a mark or indicator 36 on the rim of said support, or in other words, the support must be brought into a position 50 with its indicator 36 at the pointer 35. Therefore all that is necessary for the operator to perform before starting is to adjust the record support so that its indicator 36 is at the pointer 35, the support being 55 locked in this position by the brake lever. Then the desired record 8 is placed upon the support and turned axially until its recess 32 is at the pointer 35 and is thus in proper position. The operator then places 60 the needle of the sound box 34 into said recess 32. The music sheet 10 is then placed into the chest 2 in the conventional manner and connected with the take-up roll. Then the bellows are operated and thereby the 65 music sheet is wound upon the take-up roll

and as soon as the beginning of the slot 12 arrives at the tracker duct 13 the clutch members 28 and 29 are thrown into gear, the disk support 7 is released from the brake and is rotated at a uniform speed and the 70 music sheet is maintained at a speed commensurate with that of the disk by means of the synchronization devices above mentioned but forming no part of the present invention. 75

When the piece has been played and the sheet is to be rerolled, this is accomplished in the conventional manner by shifting the rewinding lever 37 which reverses the driving gearing from the motor in the conventional manner. By shifting the lever 37 a valve 38 is opened in the end of a tube 39, which tube in turn controls a valve 40, from which a tube 41 leads to a bellows 42 which when exhausted brings the lever 18 into position for locking the disk support. 80 85

Having described my invention what I claim as new and desire to secure by Letters Patent is:

1. The combination with a player piano, 90 comprising an air motor for moving a perforated music sheet and a talking machine comprising a spring motor for rotating a record disk, of means controlled by the perforated music sheet for automatically throwing the air motor in gear with the spring motor and after a predetermined length of time throwing said motor out of gear, substantially as set forth. 95

2. The combination with two instrumentalities, of an independent motor in each for driving an independent record device in each instrumentality, and means controlled from one record device for throwing the motor of the instrumentality to which said record device pertains into gear with the motor of the other instrumentality and also automatically throwing them out of gear at a predetermined time, substantially as set forth. 100 105 110

3. The combination with two instrumentalities, of an independent motor for each instrumentality, two record devices each driven by the motor of one of the instrumentalities, a shaft operatively driven from one motor, another shaft operatively driven from the other motor, clutch devices on said latter shaft, means controlled in the operation of one of said records for automatically throwing said clutch devices into engagement and shortly thereafter out of engagement, substantially as set forth. 115 120 125

4. The combination with a player piano, comprising a motor for moving a perforated music sheet, means for supporting the perforated music sheet, and a tracker over which said music sheet is to be moved and a phonograph comprising a motor, a record support driven by the said motor, a sound box, a needle thereon, the record support 130

- being provided with an indicator, of a pointer adjacent to the said support and means controlled in the operation of the music sheet for throwing the motor of the 5 player piano into and out of gear with the motor of the phonograph, substantially as set forth.
5. The combination with a player piano comprising a motor for moving a perforated 10 music sheet, a tracker, supports for a perforated music sheet passing over the tracker, a perforated music sheet provided in advance of the music perforations with a slot, the tracker having a supplemental duct for 15 registry with said slot, a phonograph com-
- prising a motor, a disk support, a sound box and a needle thereon, the support having an indicator, of a pointer adjacent to said support, a record on said support, said record having a recess in communication 20 with the record lines, which recess is adapted to receive the needle on the sound box, substantially as set forth.

Signed at New York city in the county of New York and State of New York this 25 15th day of July A. D. 1913.

EDWIN SCOTT VOTEY.
